US00D677304S

(12) **United States Design Patent**
Inoue et al.

(10) **Patent No.:** **US D677,304 S**
(45) **Date of Patent:** **** Mar. 5, 2013**

(54) **PROJECTOR**

(75) Inventors: **Kazuya Inoue**, Minato-ku (JP);
Toshiyuki Yamaguchi, Minato-ku (JP);
Takuji Katsutani, Ota-ku (JP)

(73) Assignee: **NEC Display Solutions, Ltd.**, Tokyo (JP)

(**) Term: **14 Years**

(21) Appl. No.: **29/406,790**

(22) Filed: **Nov. 18, 2011**

(30) **Foreign Application Priority Data**

Jun. 9, 2011 (JP) 2011-13049

(51) **LOC (9) Cl.** **16-02**

(52) **U.S. Cl.** **D16/235**; D16/230

(58) **Field of Classification Search** D16/205, D16/208, 219, 221, 225, 230-231, 234-235; D21/514; 352/34, 242; 353/100-101, 115, 353/119, 122; 396/448

See application file for complete search history.

(57) **CLAIM**

The ornamental design for a projector, as shown and described.

DESCRIPTION

FIG. 1 is a front, left side, top perspective view of a projector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a slightly enlarged top plan view thereof;

FIG. 7 is a slightly enlarged bottom plan view thereof; and,

FIG. 8 is a front, left side, top perspective view thereof showing a state in which a lens cover is closed.

The long dash short dash broken line shown in FIGS. 1, 6 and 8 represents the bounds of the claimed design while all other even broken lines represent environmental structure and are for illustrative purposes only; the broken lines form no part of the claimed design.

1 Claim, 8 Drawing Sheets
